United States Patent Office

Des. 184,470
Patented Feb. 17, 1959

184,470

IMPEDANCE MATCHING TRANSFORMER OR SIMILAR ARTICLE

Bruno Zucconi, San Francisco, Calif.

Application December 9, 1957, Serial No. 48,840

Term of patent 14 years

(Cl. D26—15)

Fig. 1

Fig. 2

Fig. 3

Fig. 4

Fig. 5

Figure 1 is a top plan view of an impedance matching transformer or similar article, showing my new design;

Figure 2 is a side elevational view, the opposite side being substantially a mirror image thereof;

Figure 3 is a bottom plan view;

Figure 4 is an end elevation view showing the connector;

Figure 5 is an opposite end elevational view thereof.

I claim:

The ornamental design for an impedance matching transformer or similar article, as shown and described.
